his Atty's.

UNITED STATES PATENT OFFICE.

ROY C. MUNRO, OF CHICAGO, ILLINOIS, ASSIGNOR, BY MESNE ASSIGNMENTS, TO KEN-
NOWAY MANUFACTURING COMPANY, A CORPORATION OF DELAWARE.

CAR-END CONSTRUCTION.

Application filed May 7, 1920. Serial No. 379,451.

To all whom it may concern:

Be it known that I, Roy C. MUNRO, a citizen of the United States, residing in Chicago, in the county of Cook and State of Illinois, have invented a new and useful Improvement in Car-End Constructions, of which the following is a specification.

This invention relates to car end constructions, and has for an object the provision of a composite end constituted of wood paneling, reinforced by metal paneling in the lower portion of the car end, to form a structure that adequately resists the end thrusts of the load in the car and at the same time is light and economical.

The invention has for other objects such other improvements or advantages in construction and operation as may be found to obtain in the structures and devices herein-
after described or claimed.

In the accompanying drawings, forming a part of this specification, and showing, for purposes of exemplification, a preferred form and manner in which the invention may be embodied and practiced but without limiting the claimed invention specifically to such illustrative instance or instances.

Figure 1 is an end elevation of a railway box car provided with a composite end constructed in accordance with the present improvements;

Fig. 2 is a vertical section of the same on the line 2-2 of Fig. 1.

The same characters of reference indicate the same parts throughout the several views.

In the illustrated embodiment of the invention, the wood paneling is constituted of an inside paneling 11 and an outside paneling 12, the inside paneling 11 being formed of horizontally arranged panel boards whereas the outside paneling 12 is formed of vertically arranged panel boards. The inside paneling 11 is laid against and secured to the end posts 13 and the diagonal braces 14 and extends horizontally between the two corner posts 15 located at the end corners of the car frame, to which corner posts the inside wood paneling is also secured. To further brace the structure there is provided a belt rail 16 located approximately midway between the top and bottom of the car end and secured in any preferred manner to the

end posts 13, the diagonal braces 14 and the corner posts 15. The inside paneling 11 is also suitably secured to the belt rail 16. Vertically, the inside paneling 11 extends approximately from the car floor to the end plate 17, as shown in Fig. 2.

The outside wood paneling 12 extends vertically from the bottom of the end sill 18 to and beyond the top of the end plate 17. This outside paneling 12 rests against the outer faces of the end sill 18 and end plate 17 and is secured to said sill 18 and plate 17 as well as to the end posts 13, the diagonal braces 14, the corner posts 15 and the belt rail 16. Horizontally, the outside paneling extends from side to side of the car end, as shown in Fig. 1. At the top of the car a sub-fascia 19 is laid against and secured to the outside paneling 12, and laid against and secured to the sub-fascia 19 is the usual fascia 20.

In accordance with the present invention, the lower section of the end structure is braced and strengthened by a metal paneling 21 which is bolted at 22 through the inside and outside paneling 11 and 12 to the end posts 13, at 23 through the two wood panelings to the diagonal braces 14, at 25 so through the two wood panelings to the corner posts 15, and is bent around and bolted to the outer side faces of the corner posts at 26. At the bottom the metal paneling is bolted to the outer face of the end sill 18 by means of a line of bolts 27. This metal paneling 21 is made exceptionally strong by constituting it of a plurality of horizontal corrugations 28, preferably of the general character disclosed in the prior patent to Thomas Nathan Russell No. 1,332,857 dated March 2, 1920. That is to say, the lower metal paneling 21 has its body constituted of parallel truncated corrugations whose oppositely presented flat faces are of less extended width than the connecting webs that truss them. Because of its position extending clear across the lower portion of the car end, the metal paneling 21 constitutes a powerful reinforcement for the lower portions of the inside wood paneling 11 and similar portions of the outside wood paneling 12, as such metal paneling is placed in a position where it resists the main thrusts

of the load in the car. The natural strength of the metal in the panelling 21 is furthermore greatly enhanced by the corrugated formation of the sheet, the horizontally corrugated body forming a powerful brace against end thrusts of the load within the car.

In order to prevent water from getting in between the lower metal panelling 21 and the outside wood panelling 12, there is provided a horizontal flashing strip 29 which extends from side to side of the car and is secured to the outside wood panelling 12 just above the upper horizontal edge of the metal panelling 21. As shown in Fig. 2 the lower edge of the flashing strip 29 is rabbeted at 30 and the upper edge of the metal panelling 21 seats in said rabbet, with the result that the outer portion of the lower edge of the flashing strip 29 overlaps the upper horizontal edge of the panelling 21. This provides a substantially water tight joint preventing the entrance of water behind the metal panelling.

The invention as hereinabove set forth is embodied in a particular form of construc-

tion, but may be variously embodied within the scope of the claim hereinafter made.

I claim:

In a car-end, in combination: end bracing members; an inside wooden panelling secured to the inner faces of said end bracing members; an outside wooden panelling secured to the outer faces of said members; metal panelling extending transversely from side to side of the car and secured against the lower portion of the outside wooden panelling, by fastening means passed through the metal panelling, the end bracing members and both wooden panellings, thereby bracing both wooden panellings and the end bracing members against the relatively greater load thrust developed within the lower portion of the car; and a flashing strip secured to said outside wooden panelling, said flashing strip extending horizontally from side to side of the car-end and having its bottom edge overlapping the top horizontal edge of the aforesaid metal panelling; substantially as specified.

ROY C. MUNRO.
